UNITED STATES PATENT OFFICE.

JOHN R. FOSTER, OF ARLINGTON, MASSACHUSETTS.

DESIGN FOR A FRAME FOR PICTURES, MIRRORS, AND SIMILAR ARTICLES.

43,922.

Specification for Design.

Patented Apr. 29, 1913.

Application filed February 6, 1913. Serial No. 746,680. Term of patent 3½ years.

To all whom it may concern:

Be it known that I, JOHN R. FOSTER, a citizen of the United States of America, residing at Arlington, in the county of Middlesex and Commonwealth of Massachusetts, have invented a new, original, and ornamental Design for a Frame for Pictures, Mirrors, and Similar Articles, and of which the following is a specification, reference also being had to the accompanying drawing, forming part thereof.

The figure of the drawing is a front elevation of a frame for the purpose described

and illustrating my new ornamental design applied thereto.

I claim:—

The ornamental design for a frame for pictures, mirrors, and similar articles, as shown.

In testimony whereof, I have signed my name to this specification, in the presence of two subscribing witnesses.

JOHN R. FOSTER.
